CLAIM

The ornamental design for a craftwork tool, as shown and described.

DESCRIPTION

FIG. 1 is a perspective view of a craftwork tool showing my new design;

FIG. 2 is another perspective view thereof, but with a cover portion closed;

FIG. 3 is yet another perspective view thereof, but with the cover portion opened;

FIG. 4 is a top plan view thereof, with the cover portion closed, as in FIG. 2;

FIG. 5 is a side elevation thereof, from a left side of FIG. 4; FIG. 6 is a side elevation thereof, from a right side of FIG. 4;

FIG. 7 is a side elevation thereof; and, FIG. 8 is a side elevation thereof.
